UNITED STATES PATENT OFFICE

91,949

DESIGN FOR A BIRD HOUSE

Frank H. Klie, Chicago, Ill.

Application February 13, 1934, Serial No. 50,709

Term of patent 3½ years

To all whom it may concern:

Be it known that I, FRANK H. Klie, a citizen of the United States, residing at Chicago, in the county of Cook and State of Illinois, have invented a new, original, and ornamental Design for a Bird House.

The following is a specification of my design, reference being had to the accompanying drawing, forming a part thereof.

I claim:

The ornamental design for a bird house substantially as shown.

In testimony whereof, I affix my signature.

FRANK H. Klie.
